Patented Dec. 5, 1922.

1,437,503

UNITED STATES PATENT OFFICE.

ANNA A. MACKENZIE, OF ELMHURST, AND RAYMOND C. BENNER, OF BAYSIDE, NEW YORK, ASSIGNORS TO UNION CARBIDE & CARBON RESEARCH LABORATORIES, INC., A CORPORATION OF NEW YORK.

COATED DRY CELL ELECTRODE.

No Drawing.

Application filed March 27, 1922. Serial No. 547,226.

To all whom it may concern:

Be it known that we, ANNA A. MCKENZIE and RAYMOND C. BENNER, citizens of the United States, residing at Elmhurst and 5 Bayside, in the county of Queens and State of New York, have invented certain new and useful Improvements in Coated Dry Cell Electrodes, of which the following is a specification.

10 This invention relates to dry cells and has particular reference to the formation of a layer of gelatinized material upon one of the electrodes of such cells, prior to the assembly of the electrodes therein. The invention is especially applicable to the manufacture of dry cells of the type in which 15 relatively easily disintegrated depolarizing bobbins are used.

The method as above broadly outlined is 20 disclosed in United States Patent 1,295,475, dated Feb. 25, 1919, and 1,375,202, dated April 19, 1921, both granted to H. F. French and R. C. Benner. According to these patents, a film or layer of paste is applied to 25 substantially the entire inner surface of zinc cups and is gelatinized thereon by suitable application of heat. In this manner the electrode is provided with a tough, tenacious coating. The procedure described makes it 30 possible to use bobbins without the sustaining fabric wrapping which is ordinarily required to prevent detached particles of depolarizer from reaching the zinc and there forming centers for destructive local action. 35 The elimination of the wrapping results in an improvement in the service characteristics of the cell and in a large decrease in the cost of production.

In the application of R. C. Benner, Serial 40 No. 450,073, filed March 5, 1921, there is described another method of obtaining these advantageous results, comprising applying cereal paste to the bobbin and gelatinizing the paste by suitable heat treatment.

45 According to the present invention, the gelatinization of the protective layer upon the zinc electrodes or bobbins of dry cells is effected by chemical means.

In the preferred form of the invention as 50 applied to lining zinc container electrodes, the interior surface of such electrodes is first moistened with a solution of a suitable gelatinizing reagent, such as zinc chlorid. Starch paste is then distributed over the

moistened surface and is gelatinized by the 55 chlorid to form a tough layer adherent to the zinc wall and base of the container. The concentration of the gelatinizing solution may vary within wide limits, say from about 30% up to saturation. We prefer to 60 use solutions containing about 40% of zinc chlorid. If rapid gelatinization is required, the more concentrated solutions should be used.

The chlorid and paste may be conveniently applied by spraying. The spray should be so directed that no layer of paste will be formed adjacent the top of the container, as this interferes with the application of the plastic seal. The amount of 70 starch should in general be not substantially in excess of that which will form a coherent layer. Other methods may of course be adopted for distributing the liquids. For example, they may be applied by brushing, 75 or by filling the zinc container and removing the surplus by decantation, suction, or the like.

In some cases, also, the paste may be applied first to the zinc and then treated with 80 the gelatinizing solution. Or the gelatinizing solution may be applied, covered with paste, and more solution then added to toughen the inner surface of the paste layer. Alternatively, dry flour, corn meal or other 85 cereal may be used instead of paste.

After the formation of the gelatinized layer, the bobbin is inserted axially in the container, and electrolyte paste is then filled into the annular space between these elements. A suitable amount of paste may be left in the container, and displaced into operative position by inserting the bobbin. If raw flour paste is used, as is customary, the cell may be placed in hot water to gelatinize 95 it. Preferably, however, the paste contains sufficient zinc chlorid, or other gelatinizing reagent, to insure its setting into a solid mass. The cell may be completed in the usual manner by placing sawdust, paper, or 100 the like, over the bobbin, and applying a plastic sealing material.

Instead of lining the zinc containers with gelatinized paste, depolarizing bobbins may be coated therewith and equivalent results 105 obtained. The bobbins may be moistened externally with zinc chlorid by spraying, dipping, or the like, and dry cereal or cereal

paste may then be applied in any suitable way. A tough coating is thus formed upon the bobbin, effectively preventing the crumpling of its surface and enabling it to be 5 safely handled and assembled with the other cell elements under conditions of manufacture on a large scale.

It is preferred to apply the gelatinizing solution first, then the cereal, but this procedure may be reversed. A single application of gelatinizable material is generally sufficient to secure a satisfactory coating, but further applications, with suitable addition 10 of zinc chlorid or the like, may of course be made. In some cases enough gelatinizing solution may be incorporated with the mix to toughen cereal applied to the surface of the 15 molded bobbin.

Zinc chlorid may be replaced by various 20 other gelatinizing agents. Calcium chlorid, for example, may be used. In general, any material capable of gelatinizing cereal paste with reasonable rapidity, and not having a deleterious effect on the cell, may be used. 25 Starch paste is well adapted for most purposes, and cereal pastes and dry cereals in general are suitable. It will be understood that the basic idea of the present invention is the chemical gelatinization of a protective 30 layer on dry cell electrodes, and various means, other than those described, for ac-

complishing this result, are within the scope of the appended claims.

We claim:

1. Process of forming a protective layer 35 upon a dry cell electrode, comprising bringing a gelatinizable material and a gelatinizing agent into reactive relation thereon.

2. Process of forming a protective layer upon a dry cell electrode, comprising applying a gelatinizing reagent to such electrode, and distributing a gelatinizable material thereupon.

3. Process of forming a protective layer upon the inner surface of a zinc container 45 electrode, comprising applying a gelatinizing reagent to such electrode surface, and distributing a gelatinizable material thereupon.

4. The invention according to claim 3, in 50 which zinc chlorid is the gelatinizing reagent.

5. Process of forming a layer of gelatinized paste upon the inner surface of a zinc container electrode, comprising spraying 55 zinc chlorid solution upon such electrode surface, and then spraying starch paste thereupon.

In testimony whereof, we affix our signatures.

ANNA A. MACKENZIE.
RAYMOND C. BENNER.
